(57) **CLAIM**

The ornamental design for a urinal screen, as shown and described.

DESCRIPTION

FIG. 1 is a top, right perspective view of a urinal screen, showing our new design;

FIG. 2 is a bottom left perspective view thereof;

FIG. 3 is a front elevation view thereof;

FIG. 4 is a rear elevation view thereof;

FIG. 5 is a left side elevation view thereof;

FIG. 6 is a right-side elevation view thereof;

FIG. 7 is a top view thereof; and,

FIG. 8 is a bottom view thereof.

The drawings include grayscale surface shading which is included to illustrate contour, not any particular color.

1 Claim, 5 Drawing Sheets
